UNITED STATES PATENT OFFICE

LOUIS S. LIFSCHELTZ, OF MITCHELL, SOUTH DAKOTA

DISPLAY RACK

Application filed July 15, 1930. Serial No. 468,089.

This invention relates to a rack for displaying articles of merchandise, more particularly for felt or straw hats and caps, but it is to be understood that a display rack, in accordance with this invention may be employed for any purposes for which it is found applicable, and the invention has for its object to provide, in a manner as hereinafter set forth, a rack of the class referred to so constructed and arranged as to enable it to be positioned within or on the top of a display cabinet or show case including means for supporting, as well as displaying articles of merchandise in a manner to be quickly discernable and for convenient removal when occasion requires.

A further object of the invention is to provide, in a manner as hereinafter set forth, a rack of the class referred to including adjustable means to enable the use of the rack for different displays with respect to articles of merchandise.

A further object of the invention is to provide, in a manner as hereinafter set forth, a display rack including sets of vertically adjustable, flat superposed supports and means for securing the supports in adjusted position with respect to each other, and by such construction and arrangement articles of varying widths can be supported and displayed in different spaced relation with respect to each other.

Further objects of the invention are to provide, in a manner as hereinafter set forth, a display rack which is simple in its construction and arrangement, strong, durable, compact, adjustable, thoroughly efficient in its use, readily assembled, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference

characters denote corresponding parts throughout the several views:—

Figure 1 is a side elevation partly in section of a display rack in accordance with this invention.

Figure 2 is a fragmentary view in perspective looking toward one end of the rack.

Figure 3 is a section on line 3—3, Figure 1.

Figure 4 is a section on line 4—4, Figure 3.

Figure 5 is a side elevation partly in section of a modified form of display rack in accordance with this invention.

Figure 6 is a view looking toward one end of the modified form of rack.

Figure 7 is a section on line 7—7, Figure 5.

Figure 8 is a section on line 8—8, Figure 7.

Referring to Figures 1 to 4 of the drawings the rack includes a pair of rectangular base members 1, 2 and each thereof is of rectangular contour. The width and length of each base member can be as desired. The base members are of like form and construction.

Each base member is formed with two spaced sets of spaced sockets disposed at the longitudinal median of a base member and opening at the upper face of the latter. One set of sockets provided in the base member 1 is indicated at 3 and the other set of sockets at 4. One set of sockets formed in the base member 2 is indicated at 5 and the other set at 6.

The distance between the inner sockets of each pair of sets of sockets is greater than the distance between the sockets of a set.

The rack includes four pairs of vertically disposed, end supports. Two pairs of end supports are associated with a base member. The end supports of one pair are indicated at 7, 8, those of another pair at 9, 10, those of another pair at 11, 12 and those of the other pair at 13, 14. The supports 7, 10, 11 and 14 provide the outer supports of said pairs of supports and the supports 8, 9, 12 and 13 form the inner supports of said pairs of supports. One pair of supports is generally indicated at A, another pair at B, another pair at C and the remaining pair at D. The supports 8, 9 of the pair of supports A, B oppose each other. The supports 12, 13 of the pair of sup-

ports C, D, oppose each other. Each of the supports is square in cross section. Each support has its inner edge formed with spaced, transversely extending grooves 15. The 5 grooves of the support 7 oppose the grooves of the support 8. The grooves of the support 9 oppose the grooves of the support 10. The grooves of the support 11 oppose the grooves of the support 12 and the grooves of the support 13 oppose the grooves of the support 15.

10 Each support has its lower end provided with a tenon 16 which is inset with respect to the inner edge of the support. The tenons 16 of the pairs of supports A, B engage in the 15 sockets 5, 6 respectively, and the tenons of the pairs of supports C, D engage in the sockets 5, 6 respectively of the base member 2. The tenons of the supports A, B engage in the base member 1. The pairs of supports 20 A, C oppose each other. The pairs of supports C, D oppose each other.

25 The rack includes two sets of superposed slats. The slats of one set coat with the slats of the other set to provide supporting means for displaying the articles of merchandise. The slats of one set are indicated at 17 and the slats of the other set at 18. Each of the slats is of rectangular transverse cross section. The slats 17 are supported by the walls 30 of the grooves in the pairs of supports A, C, and the slats 18 are supported by the walls of the grooves of the pairs of supports B, D. The supports of each pair are arranged in spaced relation and the grooves 15 of the slats 35 7, 8 align with the grooves 15 of the supports 11, 12. The slats are selectively positioned in the aligning grooves of a pair of supports and by this arrangement the slats of each set can be selectively positioned at different superposed spaced relations with respect to 40 each other.

45 When the slats 17 have been selectively positioned in the pairs of supports A, C and when the slats 18 have been selectively positioned in the pair of supports C, D, each pair of supports is adjustably clamped to said slats by binding screws 19 which extend through one of the supports of a pair and engage in the other support of the pair.

50 Each set of slats provides means whereby the supports of each pair can be connected by their tenons to a base member in adjusted spaced relation relative to each other and said two spaced sets of slats in each member permit of the two pair of supports connected therewith being adjusted in different spaced relations with respect to each other. The slats coupled to two pairs of supports can be arranged at different heights with respect to 55 the slats coupled to the other two pair of supports or the slats of one set can align with the slats of the other set.

60 In the modified form shown in Figures 5 to 7, the rack includes a pair of rectangular base members 20, 21 and the former is pro-

vided with a pair of spaced sockets 22, 23, and the latter with a pair of spaced sockets 24, 25. The sockets open at the upper face of the base members and are disposed in the longitudinal median thereof.

65 Projecting above the base member 20 is a pair of vertically disposed supports 26, 27 provided on their lower ends with tenons 28, 29 which extend into the socket 23 of the base member 20, and are secured therewith by the holdfast devices. The support 26, as well as the support 27 is provided with a vertically disposed row of spaced, transversely extending openings 31. The openings of one support align with the openings in the other support.

70 Extending upwardly from the base member 21 is a pair of vertical supports 32, 33 and which are provided at their lower ends with tenons 34, 35 respectively which engage in the sockets 24, 25 respectively of the base member 1. Holdfast devices 36 are provided for securing the supports 32, 33 to the base member 21. The support 32, as well as the support 33 is provided with a vertical row of spaced openings 34. The openings 34 in the support 32 align with the openings 34 in the support 33.

75 The supports 26, 27 are arranged in opposed spaced relation. The supports 32, 33 are arranged in opposed spaced relation. The support 26 opposes the support 32. The support 27 opposes the support 33. The openings 31 in the support 26 align with the openings 34 in the support 32. The openings 31 in the support 27 align with the openings 34 in the support 33.

80 Two sets of slats are employed in connection with the form shown in Figure 5 and the said two sets of slats perform the same function as the slats 17, 18. One set of slats forming a part of the form shown in Figure 5 is indicated at 37 and the other set at 38. The slats 37 are selectively positioned in aligning openings of the supports 26, 32 and the slats 38 are selectively positioned in aligning openings of the supports 27, 33. The two sets of slats provide supporting means for the article of merchandise, as well as displaying the latter. The slats 37, 38 can be adjusted to align with each other or the slats of one set can be positioned above the slats of the other set.

85 It is thought that the many advantages of a display rack, in accordance with this invention and for the purpose set forth can be readily understood, and although the preferred embodiment of the invention is as illustrated and described, yet it is to be understood that changes in the details of construction can be had which fall within the scope of the invention as claimed.

90 What I claim is:—

95 1. A display rack comprising a pair of opposed, spaced, end base members, each base

member provided with two spaced sets of spaced sockets opening at the upper face of the member, a pair of opposed, spaced, vertical supports selectively positioned in the 5 sockets of each of said sets of sockets, the supports of each pair having their inner edges provided with coacting grooves to form superposed slat supporting means, two sets of slats, each set of slats coacting with two pairs of supports and selectively positioned 10 in the superposed supporting means at the inner edges of the supports of the said two pairs of supports and means for clamping each pair of supports to a slat.

15 2. A display rack comprising a pair of opposed, spaced end base members, two spaced pairs of vertical supports carried by each base member, each base member provided with means whereby each pair of supports can be 20 adjusted relatively to each other and the supports of each of said pair of supports adjustable relatively to each other, two sets of slats, each pair of supports provided with means for selectively positioning the slats of the set 25 of slats therein, and means for clamping the supports of each pair to the slats when positioned in a pair of supports.

30 3. A display rack comprising a pair of spaced, opposed end base members each provided with a pair of sockets arranged in spaced relation and opening at the upper face 35 of the member, a pair of vertical supports extending into the sockets of each base member and fixedly secured to the latter, each of said 40 supports formed with a vertical row of spaced openings, the supports carried by one base member opposing the supports carried by the other base member, and slats selectively positioned in the openings of the pair of opposed supports.

45 In testimony whereof, I affix my signature hereto.

LOUIS S. LIFSHULTZ.
